2,414,656

SOUND PRODUCING INSTRUMENT

Milo F. Miller, Kansas City, Mo.

Application September 27, 1943, Serial No. 503,963

7 Claims. (Cl. 84—405)

1

This invention relates to sound producing instruments of the percussion type and has for a primary object the provision of means for developing an over-tone audible to a human ear which has become deficient in detecting tones of different frequencies.

One of the important aims of the present invention is to provide a sound producing instrument having at least two vibrating elements, each capable of emitting tones of different frequencies, which tones are so related as to develop a pulsating or an undulating over-tone audible to certain persons who have lost the property of detecting and hearing tones having the frequencies of the sounds emitted by the two respective elements.

A still further aim of the instant invention is to provide a unitary instrument having as a component part thereof, at least two sounding bars associated with resonating chambers, said bars and chambers being relatively adjustable for the purpose of developing individual sound waves of such frequency as to create an over-tone audible to the operator.

Other objects of the invention will appear during the course of the following specification, referring to the accompanying drawing wherein:

Fig. 1 is a bottom view of a sound producing instrument made in accordance with the present invention illustrating one unit of the resonating tube assembly.

Fig. 2 is a longitudinal sectional view thereof taken on line II—II of Fig. 1.

Fig. 3 is a cross sectional view taken on line III—III of Fig. 2 and looking in the direction of the arrow.

Fig. 4 is a bottom view of the sound producing instrument, completely assembled and showing a pair of tone elements.

Fig. 5 is a diagrammatical view illustrating the sound wave from a pair of sound producing instruments and showing in a schematical fashion, the undulating overtone waves; and

Fig. 6 is a wiring diagram illustrating the manner of arranging the striking means of the instrument whereby the sounding bars are successively struck at intervals.

It has been found that persons unable to detect tones of conventional frequencies may be made to hear sounds of several lengths produced by combining two frequencies to establish an over-tone. It has further been discovered that the component sounds must be altered with respect to frequencies, pitch and timbre in order to establish the over-tone audible to those hard

2

of hearing. Accordingly, sound producing instruments heretofore available, have not been satisfactory to meet the problem of providing deviations audible to those so afflicted. The instrument illustrated permits all of the necessary adjustments to produce the basic sound waves from which emanate the over-tone or undulating reverberation of the two original trains of waves.

The instrument capable of obtaining sounds audible to those afflicted with various stages of deafness comprises at least two resonating tubes 10 and associated sounding bars 12. Said resonating tubes 10 and sounding bars 12 are suitably supported by a base 14 in the nature of a housing wherein is carried a solenoid 16 for each bar 12. The striking member 18 is operated when solenoid 16 is energized. A plate 15 joins base members 14 as shown in Fig. 4.

Resonating tubes 10 are alike in length and diameter, the chamber 20 therein may be varied as to length through the medium of a pair of pistons 22 slidably disposed near the ends of tubes 10 and manually manipulable through axial rods 24.

A scale 26 carried by base 14 cooperates with pointer 28 in indicating to the operator the relative positions of pistons 22. This is particularly important since it is desired that pistons 22 be the same distance from opening 30 formed through the side of each tube 10.

Circular opening 30 is on a transverse medial line of each tube 10 and the size thereof is selectively varied by a series of shutters 32 all slidably mounted within the respective tubes 10 for movement to and from a desired position. Thus, not only can the chambers 20 of the tubes 10 be altered as to cubic capacity, but the size of openings 30 may be varied to suit conditions and present a tone quality which cooperates with frequency to establish a sound wave, characterized by having a quality capable of combining with the sound waves produced by the companion tube 10 in creating the overtone audible to those hard of hearing.

Sounding bars 12 are of different widths and lengths to produce different tones. The quality of said tones and the manner of resonating the same are not only alterable by adjustment of the parts associated with tubes 10, but may be altered by moving bars 12 toward and from opening 30 in resonating tubes 10 through the medium of supporting nuts 34 which carry bushings 36 of non-metallic material.

It is desirable to strike one of bars 12 after the other has been struck, and within the period

of time of vibration of the first struck bar—thus, two distinct sound waves of different wave lengths or frequencies are created to combine as shown diagrammatically in Fig. 5, wherein line 38 represents one frequency, line 40 the second tone frequency, and the dotted line 42 illustrates the over-tone which is of the desirable wave length.

A single operation will cause both bars to sound in the proper sequence and at the proper time when an electrical circuit such as shown in Fig. 6 is employed.

Solenoids 16 are associated with bars 12 as above set forth, and the striking elements 18 are movable when their respective coils are energized. A source of electrical current 44 in the form of a battery or the like, is connected to solenoid 16 by appropriate conductors having a switch 46 therein to open and close the circuit.

Contact points 48 are successively struck by arm 50 as it is moved through its path of travel about pivotal point 52 by solenoid 54. Thus, when switch 46 is closed, solenoid 54 will be energized and arm 50 will be drawn across point 48, one after the other. The two bars 12 will be successively struck and the second will be vibrated by its respective element 18 before the vibration period of the first to be struck is closed.

The sound waves produced as shown diagrammatically in full lines in Fig. 5, will periodically come together to produce an over-tone.

From the foregoing it will be apparent that instruments constructed as set forth, are capable of adjustment and tuning to establish a tone particularly peculiar to one hard of hearing, and that the adjustment of the two basic tones to produce the third over-tone audible to the person hard of hearing, may take place by employing the instrument described and shown. Such variations as may be required in the structure to vary the size of the chamber of the resonating tubes 10 and the size and relative position of bars 12, may be made without departing from the spirit of the invention or scope of the appended claims.

Having thus described the invention, what is claimed as new and desired to be secured by Letters Patent is:

1. A sound producing instrument of the character described, comprising at least two perforated, closed end resonating tubes; a sounding bar adjacent to each tube and opposite the perforations thereof; and manually manipulable struc-

ture mounted on each tube for moving the ends of the tube for varying the size of the chamber thereof.

5 2. A sound producing instrument of the character described comprising at least two centrally perforated, closed end resonating tubes; a sounding bar opposite the perforation in each tube respectively; means for mounting the sounding bars for movement toward and from the resonating tubes; and manually manipulable structure for moving the ends of the tubes for varying the size of the chamber of the tubes.

10 3. A sound producing instrument of the character described comprising at least two resonating tubes; a sounding bar adjacent to each tube; and structure mounted on each tube for varying the size of the chamber thereof, said tubes each having an opening opposing the sounding bar, the tubes each having means thereon for varying the size of the said opening therein.

15 4. A sound producing instrument of the character described comprising a pair of resonating tubes of like size; a sounding bar adjacent to each tube; means for varying the size of the chamber of each resonating tube respectively; mounting structure for the sounding bars having means for holding the bars predetermined distances from their respective tubes; striking means for each bar respectively, and common means for actuating said striking means at different times, said common means having parts for establishing a period between the times of striking of the bars that is shorter than the duration of vibration of the first to be struck of said sounding bars.

20 5. A sound producing instrument as set forth in claim 4, wherein the sounding bars are of different width and length.

25 6. A sound producing instrument as set forth in claim 4, wherein the sounding bars are formed to vibrate at relatively different frequencies.

30 7. A sound producing instrument of the character described, comprising a pair of resonating tubes; a sounding bar adjacent to each tube; and means for striking the bars at different times, said means having parts for establishing a period between the times of striking being shorter than the duration of vibration of the first to be struck, said tubes and the bars being relatively tuned to produce a third over-tone of deeper timbre and lower frequency than those produced by the sound emitted from the two tubes and their bars.
